UNITED STATES PATENT OFFICE.

ADONIRAM R. WILLETT, OF LOUISVILLE, KENTUCKY.

HEATING-STOVE.

No. 839,354.

Specification of Letters Patent.

Patented Dec. 25, 1906.

Application filed March 8, 1905. Serial No. 249,089.

To all whom it may concern:

Be it known that I, ADONIRAM R. WILLETT, a citizen of the United States, residing at 935 Third street, Louisville, in the county of Jefferson and State of Kentucky, have invented a new and useful Heating-Stove, of which the following is a specification.

This invention relates to heating-stoves; and the principal object of the invention is to provide a stove of novel and improved construction in which the products of combustion shall be compelled to circulate through a space between the base-plate of the stove and the ash-pit while said products are in a highly-heated condition, so that intense heat shall be radiated downward from the stove in the direction of the floor, adjacent to which the air in an apartment is always the coldest, so that the cold air shall be displaced and a perfect circulation established.

Other objects of the invention are to simplify and improve the construction and operation of this class of stoves.

With these and other ends in view, which will readily appear as the nature of the invention is better understood, the same consists in the improved construction and novel arrangement and combination of parts, which will be hereinafter fully described, and particularly pointed out in the claim.

In the accompanying drawings has been illustrated a simple and preferred form of the invention, it being, however, understood that no limitation is necessarily made to the precise structural details therein exhibited, but that changes, alterations, and modifications within the scope of the invention may be made when desired.

In the drawings, Figure 1 is a vertical sectional view of a heating-stove constructed in accordance with the principles of the invention. Fig. 2 is a horizontal sectional view taken on the plane indicated by the line 2-2 in Fig. 1. Fig. 3 is a horizontal sectional view taken on the plane indicated by the line 3-3 in Fig. 1. Fig. 4 is a detail view of the damper whereby the course of the products of combustion is controlled. Figs. 5 and 6 are sectional views illustrating modifications in the arrangement of the vertical flue.

Corresponding parts in the several figures are indicated throughout by similar characters of reference.

In the drawings the invention has been shown applied to a simple form of a sheet-metal stove, of which 10 designates the cas-

ing, which has been shown as being of cylindrical form, said casing being connected at its upper and lower ends with the top plate 11 and the base-plate 12, said top and base plates being connected in the ordinary manner by rods 13 or by other suitable means.

The ash-pit 16 is composed of an independent casing, preferably of cast-iron, having legs 17 whereby it is supported upon and elevated above the base-plate 12 of the stove. The fire-pit is spaced from the stove-casing 10 at its sides and rear end. Its front end is connected with an aperture in the front wall of the stove-casing, where a door 18 is provided to afford access to the interior of the ash-pit, said door being provided with a draft-inlet capable of regulation, as by slides 19 of ordinary construction.

The top of the casting, which constitutes the ash-pit, has an opening surrounded by an annular flange 9, which latter affords a seat for the fire-pot 14, which is flared upwardly and provided at its upper edge with a flange 8, that circumferentially engages the interior of the stove-casing, except at the front, where a recess 15 is provided for the downward passage of smoke and other products of combustion. A grate 20 is supported in any suitable manner in the bottom of the fire-pot.

At the back of the stove-casing there is a vertical flue 21, which extends the entire height of the stove-casing, of which it may be regarded as forming a part. This flue may be formed exteriorly upon the casing, as in Figs. 1, 2, and 3, or interiorly upon the casing, as in Fig. 5, or said flue may be part inside and part outside of the casing, as shown in Fig. 6. It is also to be understood that this flue may be constructed in any approved and convenient manner. At its lower end the flue 21 communicates, through an opening 22, with the interior of the stove-casing adjacent to the base-plate 12. The upper end of the flue 21 communicates with the exit-flue 23, which latter also communicates with the interior of the stove-casing through an aperture 25 in the top plate 11. A damper 24 is provided, whereby the aperture 25 and the upper extremity of the flue 21 may be alternately obstructed.

Fuel may be supplied to the fire-pot through a feed-door 27 upon the front part of the casing or through an opening in the top plate 11, for which a cover 28 is provided. An inclined deflector 26 is secured upon the inside of the casing beneath the feed-door

and directly above the recess 15 in the rim or flange 8 of the fire-pot for the purpose of preventing fuel from dropping through said recess.

5 Suitably connected with the feed-door 27 is an air-flue 29, which is directed toward the surface of the fire-pot, said flue being for the purpose of admitting air when it shall be desired to check the combustion, admission of air from the outside through the flue 29 being governed by a valve 30.

Access to the space between the bottom of the ash-pit and the base-plate 12 may be had for the purpose of cleaning said space when necessary through an aperture 7 in the stove-casing, for which a door or slide 31 is provided.

20 Baffle-plates 32 and 33 are disposed between the fire-pot 14 and ash-pit casing 16 and the interior of the stove-casing 10, said baffle-plates being extended from the rim or flange 8 of the fire-pot downwardly as far as the bottom of the ash-pit and said deflectors being disposed about midway between the 25 outlet 15 of the fire-pot and the outlet 22, which connects the stove-casing with the flue 21, the object of said baffle-plates being to compel the products of combustion to traverse the space between the bottom of the 30 ash-pit and the base-plate 12.

35 The stove can be readily adapted for burning various kinds of fuel, and, if desired, a magazine to hold a supply of fuel may be used, as indicated at 35 in Fig. 1 of the drawings, supporting-hooks 34 for such magazine being arranged upon the under side of the top plate 11 of the stove.

40 From the foregoing description taken in connection with the drawing hereto annexed, the operation and advantages of this invention will be readily understood. When the fire is first started in the stove, the damper 24 will be placed in position to obstruct the flue 21, permitting the interior of the 45 stove to communicate with the exit-flue through the aperture 24. When the fire has gained headway, the damper 24 is turned to the position shown in Fig. 1 of the drawings and obstructing the aperture 24 and the 50 products of combustion will thus be compelled to pass from the fire-pot through the recess or opening 15 in a downward direction between the stove-casing and the sides of the ash-pit, beneath the bottom of the latter,

and through the aperture 22 and vertical flue 55 21 to the exit-flue. While it is obvious that heat is radiated from the entire stove-casing, it will be specially noted that the products of combustion almost immediately after leaving the fire-pot and in a highly-heated or 60 incandescent condition will be compelled to pass through the space between the bottom of the ash-pit and the base-plate of the stove, which latter will thus be highly heated and caused to radiate heat in a downward direction 65 in accordance with the purposes of the invention.

The principal advantages of this improved stove are to be found in its extreme simplicity, the castings constituting the fire-pot and 70 the ash-pit being readily applicable to the simplest kind of sheet-metal stove construction. Economy in construction is thus insured, while economy in the consumption of fuel obviously results from the fact that the 75 heat is radiated mainly in the direction where it most is needed.

Having thus described the invention, what is claimed is—

80 In a heating-stove, a casing, top and bottom plates connected therewith, an ash-pit casing supported upon and elevated above the bottom plate, said ash-pit casing being connected with the front of the stove-casing and spaced from the latter at its sides and 85 rear end, a fire-pot supported upon the ash-pit and having at its upper end a rim contacting with the stove-casing and provided with a notch or recess for the downward passage of products of combustion, a flue or passage connecting the lower end of the stove-casing with a point of exit, and baffle-plates 90 disposed between the stove-casing and the side walls of the fire-pot and the ash-pit casing; said baffle-plates extending from the rim 95 of the fire-pot downward to the level of the bottom of the ash-pit, and said baffle-plates being also disposed between the notch in the rim of the fire-pot and the opening connecting the lower part of the stove-casing with 100 the flue leading to the exit-flue.

In testimony that I claim the foregoing as my own I have hereto affixed my signature in the presence of two witnesses.

ADONIRAM R. WILLETT.
